UNITED STATES PATENT OFFICE

156,466

POWERED TILLER

George E. Smithburn, Berkeley, Calif.

Application December 31, 1947, Serial No. 143,468

Term of patent 14 years

(Cl. D35—2)

To all whom it may concern:

Be it known that I, George E. Smithburn, a citizen of the United States of America, and a resident of the city of Berkeley, county of Alameda, State of California, have invented a new, original, and ornamental Design for a Powered Tiller, of which the following is a specification, reference being had to the accompanying drawings, forming a part thereof.

Figure 1 is a view in elevation of one side of the powered tiller, showing my new design;

Figure 2 is a view in elevation of the opposite side of such powered tiller;

Figure 3 is a plan view of such tiller;

Figure 4 is a view in elevation of the front end of such powered tiller; and

Figure 5 is a view in elevation of the rear end thereof.

Figure 6 is a perspective view of the tillage unit detailed.

I claim:

The ornamental design for a powered tiller, substantially as shown.

GEORGE E. SMITHBURN.
